UNITED STATES PATENT OFFICE.

FREDERIC K. PLYMPTON, OF BREWSTER, NEW YORK, ASSIGNOR TO NAOMI D.
PLYMPTON, OF SOUTHPOR, CONNECTICUT.

BOTTLE CLOSURE.

Application filed August 14, 1924. Serial No. 732,017.

The invention relates to closures for sealing milk bottles and the like, and more particularly to closures of the class in which a closure consists of a thin disk of paper material having a leaf-like tab or handle which is taken hold of and pulled upon in effecting removal of the disk from the seat to which it has been applied in the mouth of a bottle or jar.

10 In some instances the lifting tab or handle is integral with the material of the disk, being formed by cutting partially through the disk around the outline of the tab or handle, then horizontally splitting the material so as to separate the tab or handle from the underlying portion of the disk except at the outer end of the tab or handle, and then pressing the tab or handle back into place. In other instances a tab or handle formed as a separate piece is attached to the disk. Thus, in the case of one form a recess is formed in the upper side of the disk, and a tab or handle formed as a separate piece is placed in such recess. In all those 25 instances, a staple or the like is set in the closure at the outer end of the tab or handle, in the first instances to serve as a reinforce for the tab or handle to guard against it being entirely torn away when pulled upon, and in the latter instances to fasten the tab or handle to the disk at such end.

A serious drawback or disadvantage in the case of such closures heretofore has been the tendency of the staple to tear out of the 35 disk while the tab or handle is being pulled upon to extract the closure from the seat to which it has been applied in the mouth of a jar or bottle. In many cases, this tendency is due in part to the fact that only a portion of the thickness of the material of the disk underlies the tab or handle; and is increased by the weakening of such portion as a result of the latter being partially 40 cut through by the clinched extremities of the limbs of the fastening staple. In practice the said extremities have been clinched at the under side of the disk, in the thinned portion of the disk immediately beneath the tab or handle. The said thinned portion 45 has had to take the entire strain of the pull, and has frequently failed to meet the requirements, especially after having become

more or less soaked with the contents of the jar or bottle.

The general object of the invention is to 55 reinforce the tab or handle by providing for distributing the strain in extracting a closure so that in large part it shall be withstood by the portions of the disk at opposite sides of the tab or handle.

60 The invention consists in a closure of the class aforesaid having a staple set at the attaching end of the tab or handle, with the limbs of the staple passed through from one face to the other of the closure, then extended laterally beyond the sides of the tab or handle, and then anchored to the material of the disk at points spaced laterally outward from the side-margins of the tab or handle.

70 Illustrative embodiments of the invention are shown in the drawings, in which latter, Fig. 1 is a top view of one of such embodiments.

Fig. 2 is a bottom view thereof.

Fig. 3 is a view in section on line 3, 3, of Fig. 1.

Fig. 4 is a top view of a second embodiment.

Fig. 5 is a bottom view thereof.

Fig. 6 is a view in section on line 6, 6, of Fig. 4.

75 I is the cap or closure of disk form, 2 in Figs. 1, 2 and 3 is a lifting tab or handle integral with the material of the disk and formed by cutting partially through the body of the disk along the outline of the tab or handle, and then horizontally splitting the tab or handle portion and pressing the same back into its original position. 3 indicates the horseshoe cut forming the outline 80 of the tab, 4 is the closed portion, i. e., head or bridge portion, of the staple, said portion being located at and extending crosswise with relation to the attaching portion 85 of the handle, while the limbs 5, 5', of the said staple pass through the disk at the base of the tab and extend on the bottom of the disk to points within its periphery spaced laterally outward from the side-margins of 90 the tab where they again pass thru the disk to the upper surface where the ends 6, 6' are clinched. While in Figs. 1, 2 and 3 the staple is shown with the closed portion ly-

ing within the outline of the tab and with the limbs on the bottom of the closure extending outwardly in relation thereto, it is evident that the relative positions of the parts of the staple may be varied from the construction shown.

In order to facilitate the use of the closures in capping machines preferably the closure is compressed in order that the staple may be either wholly or partially imbedded in the disk in which case this method of reinforcing the tab is particularly effective as the pulling strain takes place primarily on the bottom of the closure against the full thickness of the latter as the clinched end only lies over a small portion of the bottom limb and consequently the closure where the strain is exerted is not weakened by the cutting or scoring of the closure by two thicknesses of wire.

Figs. 4, 5 and 6 show another common form of closure to which the invention is shown applied. 1 is the disk having a cut away portion 7 forming a recess in the thickness of the disk in which the handle or tab 8 lies. This handle or tab is attached to the disk by means of the staple 9 the limbs of which 10, 10' pass thru the handle and the material of the disk and extend on the bottom of the disk to points within the periphery where they again pass through the disk to the upper surface where they are clinched. In the drawings the points where the limbs again pass through the disk to the upper surface lie outside the cut away recess in the upper surface of the closure in order that the pulling strain may be resisted by the entire thickness of the disk. This is a particularly valuable feature of the invention for as this type of cap is commonly made the tab is applied or attached to the disk by driving a staple through it and the weakened cut away recessed portion of the disk and clinching the limbs of the same inwardly on the bottom of the disk. It will be apparent that this materially weakens the holding capacity of the tab when strain is applied to it in removing the disk from the bottle in which it has been seated.

The various views of the drawings clearly illustrate the important feature which has been mentioned, that in conformity with the invention the limbs of the fastening staple are in anchoring engagement with the material of the disk at points spaced laterally outward from the side-margins of the tab or handle, the advantage being that the thickness of the disk, at the opposite sides of the tab or handle, is utilized to withstand the pulling strain when the tab or handle is pulled upon in extracting the closure from a jar or bottle.

In the drawings the extremities of the limbs of the fastening staple are shown turned toward each other so that they over-

lie the outwardly extending portions of the staple limbs at the back or underside of the disk. Ordinarily this relation of portions of a staple at opposite faces of a disk is undesirable since when the staple is impressed into the thickness of the material of the disk to facilitate the use of the closure in a capping machine, the effective strength of the intermediate portion of the disk is reduced. However, it will be perceived that the effect of locating the different portions of the staple at the opposite sides of the disk in the relation described, is minimized in the case of my invention. The extremities 6, 6', Figs. 1 and 3, and 11, 11', Figs. 4 and 6, may be otherwise disposed in practice if desired.

I claim:

1. A bottle closure having a recess in its upper side, a lifting tab occupying such recess, and a reinforcing member in the form of a staple with its closed portion lying at the base of the lifting tab with its limbs passing through the material of the closure within the width of said tab and extending on the bottom of the closure laterally to points within its periphery outside the width of the tab, again passing through the closure to the upper surface where the ends are clinched.

2. A bottle closure having a lifting tab which is formed by the horizontal splitting and raising of a portion of the same, one edge forming a hinge, in combination with a wire staple having its limbs driven through the body of the closure at the hinge edge of the tab, the said limbs extending on the bottom of the closure to points within the periphery laterally beyond the sides of the recess occupied by said tab, and passing again through the body of the closure to the upper surface and clinched.

3. A bottle closure having a lifting tab which is formed by the horizontal splitting and raising of a portion of the same, one edge forming a hinge, in combination with a wire staple, the closed portion of which lies at the base of the tab with its limbs passing through the body of the closure within the outline of the tab to the other surface of the closure and extending laterally thereon to points outside the outline of the tab where they again pass through the body of the closure to the first surface where the ends are clinched.

4. A bottle closure comprising a thin disk, a leaf-like lifting handle, and a staple having its head or bridge portion located at and extending crosswise relative to the attaching portion of the handle, the said staple having its limbs passed through the closure at the said attaching portion, with the extremities of the said limbs extended in opposite directions and in anchoring engagement with the disk at points spaced lat-

erally outward from the side-margins of the said handle.

5. A bottle closure comprising a thin disk having a recess in the upper surface thereof, and a lifting handle occupying the recess, and in combination therewith a staple having the limbs thereof passed through the closure at the attaching portion of the han-

dle with said limbs extended on the bottom of the closure to points outside the recess 10 and passed through the disk to the upper surface thereof and clinched.

In testimony whereof I hereunto affix my signature.

FREDERIC K. PLYMPTON.
